(57) **CLAIM**

The ornamental design for a floral fire suppressant ball, as shown and described.

DESCRIPTION

FIG. 1 is a front perspective view of a floral fire suppressant ball showing my new design; and,

FIG. 2 is a side perspective view thereof.

All sides of FIGS. 1 and 2 not shown form no part of the claim design.

1 Claim, 2 Drawing SheetsFIG. 1

FIG. 2
